UNITED STATES PATENT OFFICE.

VICTOR DURAND, JR., OF VINELAND, NEW JERSEY, ASSIGNOR, BY MESNE ASSIGNMENTS, TO CALORIS MANUFACTURING COMPANY, A CORPORATION OF DELAWARE.

PROTECTOR FOR THE NECKS OF BOTTLES.

941,769.

Specification of Letters Patent. Patented Nov. 30, 1909.

Application filed March 7, 1908. Serial No. 419,760.

To all whom it may concern:

Be it known that I, VICTOR DURAND, Jr., a citizen of the United States, residing in Vineland, county of Cumberland, State of New Jersey, have invented a new and useful Protector for the Necks of Bottles, of which the following is a specification.

My invention relates to a new and useful vessel for the conveyance or storage of liquids and consists in providing a protector for the neck of a vessel.

It further consists of other novel details of construction, all as will be hereinafter fully set forth.

Figure 1 represents a vertical sectional view of a vessel for the conveyance or storage of liquids, a portion only of the glass receptacle being sectioned. Fig. 2 represents a sectional view of a portion of the device on an enlarged scale.

I have found in practice that in the vessels now in use upon the market for the conveyance or storage of liquids, owing to the fact that the inner wall of the neck of the vessel which is composed of glass, is exposed, that the same will become easily broken, thus destroying, immediately, the effectiveness of the vessel.

My invention is designed to overcome these defects, and in the drawings I have shown an embodiment for carrying out my invention, but it will be evident that other instrumentalities may be employed and the arrangement of the parts may be varied without departing from the spirit of my invention, and I do not therefore desire to be limited in every instance to the exact construction shown and described but desire to make such changes as may be necessary.

Similar numerals of reference indicate corresponding parts in the figures.

Referring to the drawings:—1 designates a vessel for the conveyance or storage of liquids, the same consisting of the two receptacles 2 and 3, which are preferably of glass and are suitably connected together, forming the space 4 therebetween, from which the air is evacuated or exhausted forming a vacuum between the receptacles, the walls of which having been previously supplied with a suitable coating of silver 5.

6 designates a casing which is adapted to receive the receptacles, said casing being preferably of metal and being formed to provide a space between it and the outer re-

ceptacle in which space is adapted to be seated any suitable means for holding the receptacles in proper position. In the present instance I have shown a corrugated cardboard 7 for this purpose. The neck of the casing 6 is formed with threads 8 and is turned inwardly forming the top of the receptacle and then downwardly around the inner wall of the neck of the glass receptacle 2, it being understood that in this way I form a guard or protector 9 for the neck of the receptacles, said guard extending downwardly a suitable distance into the neck and serving at the same time as an additional means for positively holding the receptacles in proper position with respect to the casing. From this it will be understood that the necks of the receptacles of glass are thoroughly protected and are thus prevented from breakage which so often occurs when the stopper or cork is inserted therein, for in the present construction the stopper of the receptacle will contact only with the metal guard.

While I have shown the guard as being integral with the casing it will of course be apparent that the same can be formed separately therefrom and connected therewith in any suitable or desired manner, the principle of the guard being to protect the neck of the glass receptacle as before stated.

Having thus described my invention, what I claim as new and desire to secure by Letters Patent, is:—

1. In a device of the character described, receptacles suitably connected and having a vacuum therebetween, and a casing for said receptacles inclosing the same and provided with a guard or protector extending within the neck of the inner receptacle.

2. In a device of the character described, a plurality of receptacles suitably connected and having a vacuum therebetween, a casing for said receptacles, means between the outer receptacle and said casing for holding the parts in proper position, and a rigid protector carried by the casing and projecting within the neck of the inner receptacle and closing at the top the space between the casing and the outer receptacle.

3. In a device of the character described, a plurality of receptacles suitably connected together and having a vacuum therebetween, a casing for said receptacles, means for holding the receptacles in proper position

within said casing, and a guard or protector integral with said casing and projecting within the neck of said receptacles and serving as additional means for holding said receptacles in proper position within said casing.

4. In a device of the character described, a plurality of receptacles suitably connected together and having a vacuum therebetween,
10 a casing for said receptacles, and means at the upper end of said casing forming a closure for the upper end thereof, and provided with a protector projecting within the neck of the inner receptacle and aiding
15 in holding said receptacles in proper position within the casing.

5. In a device of the character described, a plurality of receptacles suitably connected together and having a vacuum therebetween, a casing for said receptacles, and means at 20 the upper end of said casing forming a closure for the upper end thereof and resting upon the upper end of the portion connecting said receptacles, and provided with a protector projecting within the neck of the 25 inner receptacle and aiding in holding said receptacles in proper position within the casing.
